UNITED STATES PATENT OFFICE.

JOSEPH A. VOGEL, OF WILMINGTON, DELAWARE.

FURNITURE-BUFFER.

No. 895,215.

Specification of Letters Patent.

Patented Aug. 4, 1908.

Application filed August 27, 1907. Serial No. 390,362.

To all whom it may concern:

Be it known that I, JOSEPH A. VOGEL, a citizen of the United States, residing at Wilmington, in the county of New Castle and State of Delaware, have invented new and useful Improvements in Furniture-Butters, of which the following is a specification.

This invention relates to furniture buffers, and it has for its object to simplify and improve the construction and operation of this class of devices, and to provide a buffer which may be readily applied to the legs, backs, and other portions of furniture for the purpose of avoiding marring the floor or walls engaged thereby and for other purposes for which furniture buffers are customarily employed.

With these and other ends in view which will readily appear as the nature of the invention is better understood, the same consists in the improved construction and novel arrangement and combination of parts which will be hereinafter fully described and particularly pointed out in the claims.

25 In the drawing, Figure 1 is a perspective view showing the preferred form of the buffer applied in position for operation. Fig. 2 is a vertical sectional view of the same. Fig. 3 is a top plan view showing the buffer detached. Fig. 4 is a vertical sectional view showing the slightly modified form of the buffer. Figs. 5, 6, and 7 are sectional detail views illustrating progressive steps in the manufacture of one form of the buffer.

35 Corresponding parts in the several figures are denoted by like characters of reference.

The improved buffer includes a cushion A which is preferably made of india rubber or of a suitable composition containing rubber; 40 said cushion being of any desired size and shape, but preferably provided with inclined side walls 1 and with a flat or level inner face 2 which is disposed at an acute angle to the side walls.

45 A fastening member is provided which, as a whole, is designated F; said fastening member comprises a pointed shank which may be in the nature of a tack 3 as shown in Fig. 2 of the drawings or it may be in the 50 nature of a screw as shown at 4 in Fig. 4; the shank is provided with a head 5 which is preferably integral therewith, and coextensive with the face 2 of the cushion member. When the shank is in the nature of a screw, 55 the head is provided with a notch 6 extending diametrically across the shank and adapt-

ed to be engaged by the bit of an ordinary screw driver.

The cushion member A is connected with the fastening member F by means of a connecting or assembling member C consisting of a ring or annulus comprising an annular flange 7 engaging the walls of the cushion member adjacent to the head of the fastening member, upon which said cushion member abuts, and a lateral flange 8 which is turned down upon the side of the head of the fastening member from which the pointed shank projects.

The assembling member C may be produced or manufactured in various ways; a preferred method being illustrated in Figs. 5, 6 and 7 of the drawings by reference to which it will be seen that the flat ring 9 having a central aperture 10 is provided, the same being struck or stamped from a sheet of metal, after which the inner portion of the annulus is struck downward to form the annular cushion engaging flange 7. The outer portion of the annulus 9 is afterwards struck or bent upward to form an approximately cylindrical collar as shown at 11 in Fig. 7; and as it is manifestly desirable to avoid bending the metal twice in the same plane, the collar 11 will be separated from the flange 7 by an annular shoulder 12. This shoulder will afford a very desirable supporting medium for the head 5 of the fastening member which, in this event instead of being coextensive with the adjacent face of the cushion member will 90 be of a slightly greater area. The parts having been assembled by first depositing the cushion member within the annular flange 7 and afterward adjusting the fastening member adjacent thereto, are finally connected 95 by turning down the collar 11 upon the head of the fastening member to form a flange which has been designated 8 in Figs. 2 and 3.

From the foregoing description taken in connection with the drawings hereto annexed, the operation and advantages of this invention will be readily understood. The construction is simple and inexpensive, and buffers constructed in accordance with the invention are capable of being very readily 105 and conveniently applied in position for operation, or detached, as occasion may demand. When the fastening medium consists of a pointed tack, a few blows with a hammer will be found sufficient to drive the 110 same; when the fastening medium is a screw, it may be readily turned as it will be found

that the parts will be assembled with sufficient rigidity for this purpose owing to the large extent of the screw head upon which the face of the cushion member abuts. After 5 the cushion member has become worn, if it should be found difficult to unscrew the device, the remains of the cushion member may be pried out, and a screw driver may then be utilized to remove the fastening screw, the 10 latter being provided with a notch 6 for such an emergency.

Having thus fully described the invention, what is claimed as new is:—

1. A furniture buffer comprising a cushion 15 member, a fastening member consisting of a shank having a head approximately coextensive with and bearing against the inner face of the cushion member, and an assembling member having an annular flange extending around and engaging the cushion member near the inner end thereof and also 20 extending around the edge of the head of the fastening member, said assembling member being further provided with an inturned lateral flange engaging the back of the head of 25 the fastening member.

2. A furniture buffer comprising a cushion

member, a fastening member consisting of a pointed shank having a head approximately coextensive with the inner face of the cushion member, an assembling member having an annular retaining flange, an inturned lateral holding flange engaging the back of the head of the fastening member, and an intermediate shoulder or offset. 35

3. A furniture buffer comprising a cushion member, an annular assembling member having a retaining flange engaging the side walls of the cushion member, an annular inturned holding flange and an intermediate shoulder 40 or offset, and a fastening member having a head supported upon said shoulder or offset adjacent to and in engagement with the inner face of the cushion member, said head being engaged by the annular inturned holding 45 flange of the assembling member and provided with an outward extending pointed shank.

In testimony whereof I affix my signature in presence of two witnesses.

JOSEPH A. VOGEL.
